MOTORCYCLE SADDLEBAG

William J. Harley, Milwaukee, Wis., assignor to Harley-Davidson Motor Co., Milwaukee, Wis.,
a corporation of Wisconsin

Application October 18, 1952, Serial No. 21,887

Term of patent 7 years

(Cl. D90—3)

To all whom it may concern:

Be it known that I, William J. Harley, a citizen of the United States of America, residing at Milwaukee, in the county of Milwaukee and State of Wisconsin, have invented a new, original, and ornamental Design for a Motorcycle Saddlebag, of which the following is a specification, reference being had to the accompanying drawing, forming part thereof.

Fig. 1 is a side elevational view of a motorcycle saddlebag showing my new design.

Fig. 2 is a top plan view thereof.

Fig. 3 is an end elevational view thereof.

Fig. 4 is a cross sectional view taken along the line 4—4 of Fig. 2.

I claim:

The ornamental design for a motorcycle saddlebag, as shown.

WILLIAM J. HARLEY.
